UNITED STATES PATENT OFFICE.

AUGUSTUS M. HENRY, OF NEW YORK, N. Y.

AMUSEMENT DEVICE.

1,269,279.

Specification of Letters Patent. Patented June 11, 1918.

Application filed July 29, 1916. Serial No. 111,979.

To all whom it may concern:

Be it known that I, AUGUSTUS M. HENRY, a citizen of the United States, residing at New York, in the county of New York and State of New York, have invented certain new and useful Improvements in Amusement Devices, of which the following is a specification.

This invention relates to games of skill, and more particularly to shooting galleries; either for providing private amusement or for public use in consideration of a fee or charge, or otherwise, and may be carried out by embodying the essential features of any known game or contest, such as baseball, football, lacrosse, polo, cricket, etc., in a shooting gallery or the like, so constructed that any person may exercise his skill or aim, in connection therewith, to effect recitation of various characteristic features of the particular game thus embodied.

The invention has for its object the provision of an improved target of the kind described and illustrated but not claimed in my former application No. 582609, filed September 19, 1910. This former application has, since the filing of this present application, matured into Patent, No. 1,193,260.

The present invention involves the provision of several targets at different points in the path of advance of a player in a game, as the base points of a base-ball field, in combination with indicating or controlling means controlled by the targets when they are fired at and hit in predetermined succession. The present application, therefore, is a continuation of said former application No. 582609, being based on a partial structural disclosure therein.

The present invention, and other objects and aims thereof, will be fully understood from the following.

In the accompanying drawings illustrating a preferred embodiment of the invention, Figure 1 is a front elevation of the apparatus; Fig. 2 is a section on the line 2—2 of Fig. 1; Fig. 3 is a rear elevation, showing the bulbs, the magnets, and the parts operated by the magnets; Fig. 4 is a perspective view of one of the locking means and the segmental target and contacts associated therewith,—looking in the direction of the arrow 4' of Fig. 3, with the board assumed cut on the line 4—4 of Fig. 3; Figs. 5, 6, 7 and 8 show in rear elevation fragments of the board adjacent the various locking means for the first, second and third base and home-

plate segmental targets, with these locking means removed to show the various contacts associated with the target segments; and Fig. 9 is a diagrammatic view, showing the wiring for the bulbs and magnets of Fig. 3 and the contacts of Figs. 3, 5, 6, 7 and 8.

The background or supporting board 10 is provided with a representation of a baseball field as shown in Fig. 1, the pitcher's position being indicated by a slot 11 and the home plate being indicated at 12. The endless band 13, on which the baseball 14 is painted, is continuously driven at a uniform speed in the direction of the arrows of Figs. 1 and 3. The band passes through the upper slot 11 and a lower slot 15 and over the idler roller 16, one of which rollers is driven by a motor 17 suitably energized. During the operation of the motor the ball is thus at regular intervals apparently pitched down from the pitcher to the catcher.

Adjacent the home plate 12 is a seven-segment target 18; adjacent first base is a six-segment target 19; adjacent second base is a five-segment target 20; and adjacent third base is a four-segment target 21. As indicated, each segment of these four targets is fixed on its own rod 22, normally held a fixed distance away from the front face of board 10 by means of an expansile spring 23 coiled about the rod, a collar 24 fixed on each rod limiting the action of the spring.

In order to prevent any of these target segments being moved upon the striking of a bullet thereagainst, except at such times as they are released by electromagnetic means controlled by the band 13, spring-held locking means are provided to coact with the ends of the rods 22 which protrude beyond the rear face of the supporting board. The locking means provided for the third base target 21 is disclosed very clearly in Fig. 4. This locking means comprises a rocking plate 21^a pivotally mounted on four parallel links 25. The plate is normally held in locking position by means of a pair of sufficiently strong retractile springs 26. As indicated in Fig. 3, similarly mounted spring-held plates 20^a, 19^a and 18^a are provided, respectively, for the second base target 20, the first base target 19 and the home-plate target 18.

The movable armatures 27 of the solenoids 21^a, 20^a, 19^a and 18^a are attached to the rocking plates by links 28. Thus while any one of such solenoids is energized, the appropriate rocking plate is elevated by a

push of link 28 against the springs 26, and the target segments of the rods 22 below this rocking plate are free to vibrate when struck by a missile. These solenoids become energized only when a preferably flexible metal strip 29 on the band 13 bridges a pair of normally isolated contacts 30 fixed to the rear of the supporting member 10 and forming parts of a suitable circuit or circuits within which are interposed the solenoids.

Such circuits are clearly shown in Fig. 9, and will be hereinafter described in detail.

Interposed in a suitable circuit or circuits, also shown clearly in Fig. 9, and herein-after described in detail, are a bulb 18^B, and a plurality of solenoids 19^B, 20^B and 21^B. The bulb and solenoids are normally deenergized, since the circuits within which the same are interposed are all normally gaped at one of the contacts 31 shown best in Figs. 4 to 8 inclusive.

The first base solenoid 19^B when energized, pushes on the loose armature therein pivoted to an arm offset from a first base signal 32 pivoted as indicated. This signal, due to the spring 34, is normally in the illustrated indicative position relative to the base opening 19^P, and in that position may indicate the fact that a "man" is not on the base or has just been put out at the base. As soon as the solenoid 19^B is energized, however the signal 32 swings up and exposes the word "Safe" through the opening 19^P; an ear carried by the signal becoming locked above a tooth 36 on a latch 37 pivoted as shown. A compression spring 38 maintains the ear and latch in engagement to hold the signal in its elevated "safe" position until the latch is positively released.

A second base opening 20^P and a third base opening 21^P are similarly equipped with similar signals and latches to cooperate as described when the solenoids 20^B and 21^B are energized.

Thus a safe indication may be given at the first, second and third bases by means of the solenoids 19^B, 20^B and 21^B. As to the home-plate, it is preferred to give it merely a momentary safe indication, since such an indication at that base registers the scoring of a "run"; and consequently the bulb 18^B is located behind the home-plate opening 18^P to momentarily illuminate the translucent insert 18^S.

In order to positively release the latches 37 when say the efforts of a contestant or a pair of contestants are concluded, thereby to reset the apparatus for a new contest, magnets 19^C, 20^C and 21^C, normally deenergized, are positioned adjacent the free ends of the latches. These magnets are interposed in a common circuit, normally open but adapted to be closed manually, all as hereinafter described in detail in connection with Fig. 9.

Interposed in a suitable circuit or circuits, also shown clearly in Fig. 9 and herein-after described in detail, are a plurality of "out" bulbs D, D', D''. Each bulb is positioned in back of a translucent insert 39 set in right, center and left field openings 40. Each of these bulbs is adapted to give a momentary flash to illuminate the adjacent insert 39 to indicate say a "fly-out" to the appropriate field position.

The collars 24 on the target-segment rods 22, and the individual contacts 31 for each of such collars, shown structurally most clearly in Fig. 4 are shown diagrammatically in Fig. 9, this figure being a diagrammatic representation of the arrangement of the electrically operated parts and their circuits as carried on the rear of the supporting board 10, as shown in Fig. 3. Thus the group of collars and contacts at the bottom of Fig. 9 correspond to the group similarly placed on Fig. 3, that is, belong to the home-plate target 18; and the similar groups shown at the top, right and left of Fig. 9 correspond to the groups to the top, left and right of Fig. 9. The collars 24 are diagrammatic, in that the rear extensions of the rods 22 beyond the collars are omitted in Fig. 9 and in that the collars are marked "R", "L", "C", etc., to indicate the marking or scoring value of the appropriate target segment.

Referring now to the circuits of Fig. 9 the solenoids 18^A, 19^A, 20^A and 21^A are normally deenergized to lock all the target segments against vibration, since the strip 29 on the traveling belt 13 has not yet bridged the contacts 30, and therefore these solenoids are interposed in parallel branches of an open circuit as follows: Starting from the battery 41, a wire 42 leads to one of the contacts 30, the other contact 30 having a wire 43 leading therefrom to ground and having interposed therein the solenoid 20^A. A wire 44 leads from the wire 43 to ground and has interposed therein the solenoid 21^A. A wire 45 leads from the wire 44 to ground and has interposed therein the solenoid 19^A. And a wire 46 leads from the wire 45 to ground and has interposed therein the solenoid 18^A. Thus all these solenoids will be energized during the time the strip 29 is bridging the contacts 30, and not otherwise; and while the contacts are thus bridged, all the locking plates of Fig. 3 will be moved away from the rear of the supporting board 10 to permit all the collars 24 to vibrate with the target segments. Then and then only may a target segment be struck to cause a collar 24 to touch its cooperator contact 31 and thus bring about an actuation of one of the result-recording instrumentalities.

Deferring for a moment further description of the circuits of Fig. 9, a playing of the game according to the present embodiment

is started by firing first at the home-plate target 18 until a base hit is made, that is, until one of the segments of the target 18 is struck thereby to cause a safe indication to be given by one of the signals 32. If such a safe indication be given on the first base opening 19^P, the first base target 20 is thereafter fired at until a base hit is made; if, however, such a safe indication was given at the second base opening 20^P, the second base target 20 would thereafter be fired at until a base hit was made; and if such a safe indication was given at the third base opening 21^P, the third base target 21 would thereafter be fired at until a base hit is made; while obviously if such a safe indication was given by a flashing of the bulb 18^B, that is, if a home run was made, the first base target would again be fired at as before in an endeavor to score another run. When a player is firing at the first base target 19, after successfully playing at the home target as described, various suitable indications may be obtained as the result of firing at such first base target 19, but in such case, however, the number of positive indications is only three, that is, a one base, two base or three base advance, and hence the first base target has one less segment than the home-plate target. In the same way, after successfully playing at the home-plate and first base targets, or after a second base advance from the former, one of two safe indications may be obtained as the result of firing at the second base target 20; that is, a one base or a two base advance, and hence the second base target has two less segments than the home-plate target. In the same way, and after successful plays at the home-plate, first base and second base targets, or at one or more thereof, a safe indication may be obtained as the result of firing at the third base target, but only one such indication, since in the actual game a 45 base runner on third base can do no more than make a one base advance, that is, come home.

Thus the home-plate target is provided with four segments "1", "2", "3" and "H" indicating respectively, one, two and three base advances and a home run. In the same way the first base target 19 is provided with three segments "1", "2" and "3" indicating respectively, one, two and three base advances. In the same way the second base target 20 is provided with two segments "1" and "2" indicating respectively one and two base advances. And in the same way the third base target 21 is provided with one 60 segment "1" indicating a one base advance.

But all the four targets are provided with three segments lettered "L", "C" and "R" indicating respectively an "out" to "left field", "center field" and "right field".

65 Referring again to Fig. 9, assume that the

strip 29 has bridged the contacts 30 and consequently all the target segments are free to vibrate when struck by a missile.

Upon striking the segment "H" of the target 18, the segment "3" of the target 19, the segment "2" of the target 20 or the segment "1" of the target 21, a run is registered by a momentary flashing of the bulb 18^B. This is so because of the following connections: A wire 47 leads from the battery 41 and has 75 branches each of which goes to one of the contacts 31. From the collar 24 on the rod 22 which supports the segment "H" of the target 18 a wire 48 having the bulb interposed therein leads to ground back to the 80 battery. From the collar 24 associated with the segment "3" of target 19 a wire 49 leads to the wire 48, to the bulb, to ground, back to the battery. From the collar 24 associated with the segment "2" of the target 20, a 85 wire 50 leads to the wire 49, to the wire 48, to the bulb, to ground, back to the battery. And from the collar 24 associated with the segment "1" of the target 21 a wire 51 leads to the wire 49, to the wire 48, to the bulb, to 90 ground, back to the battery.

Upon striking the segment "3" of the target 18, the segment "2" of the target 19, or the segment "1" of the target 20 a "man on third" is registered by the actuation of 95 solenoid 21^B. This is so because of the following connections, in addition to the wire 47 which leads from battery 41 and has branches each of which goes to one of the contacts 31. From the collar 24 associated 100 with the segment "3" of the target 18 a wire 52 having the solenoid 21^B interposed therein leads to ground, back to the battery. From the collar 24 associated with the segment "2" of the target 19 a wire 53 leads to the 105 wire 52, to the solenoid, to ground, back to the battery. And from the collar 24 associated with the segment "1" of the target 20 a wire 54 leads to the wire 52 to the solenoid, to ground, back to the battery.

Upon striking the segment "2" of the target 18 or the segment "1" of the target 19, a "man on second" is registered by an actuation of the solenoid 20^B. This is so because of the following connections, in addition to the wire 47 which leads from the battery 41 and has branches each of which goes to one of the contacts 31. From the collar 24 associated with the segment "2" of the target 18 a wire 55 having the solenoid 20^B interposed therein leads to ground, back to the battery. And from the collar 24 associated with the segment "1" of the target 19 a wire 56 leads to the wire 55, to the solenoid, to ground, back to the battery.

Upon striking the segment "1" of the target 18, a man on first is registered by an actuation of the solenoid 19^B. This is so because of the following connections, in addition to the wire 47 which leads from the 130

battery 41 and has branches each of which goes to one of the contacts 31. From the collar 24 associated with the segment "1" of the target 18 a wire 100 having the sole 5 noid 19^B interposed therein leads to ground back to the battery.

Upon striking the segment "L" on any of the four targets, an "out to left field" is registered by a momentary flashing of 10 bulb D. This is so because of the following connections, in addition to the wire 47 which leads from the battery 41 and has branches each of which goes to one of the contacts 31. From the collar 24 associated with the "L" 15 segment of the target 18 a wire 57 having the bulb D interposed therein leads to ground, back to the battery. From the collar 24 associated with the "L" segment of the target 19 a wire 58 leads to the wire 57, 20 to the bulb, to ground, back to the battery. From the collar 24 associated with the "L" segment of the target 20 a wire 59 leads to the wire 57 to the bulb, to ground, back to the battery. And from the collar 24 associated with the "L" segment of the target 21 a wire 60 leads to the wire 59, to the wire 57, to bulb, to ground, back to the battery.

Upon striking the segment "C" of any 30 of the four targets, an "out to center field" is registered by a momentary flashing of bulb D'. This is so because of the following connections, in addition to the wire 47 which leads from the battery 41 and has branches 35 each of which goes to one of the contacts 31. From the collar 24 associated with the "C" segment of the target 18 a wire 61 having interposed therein the bulb D' leads to ground, back to the battery. From the collar 24 associated with the "C" segment of the target 19 a wire 62 leads to the wire 61, 40 to the bulb, to ground, back to the battery. From the collar 24 associated with the "C" segment of the target 20 a wire 63 leads to the wire 61, to the bulb, to ground, back to the battery. And from the collar 24 associated with the "C" segment of the target 21 a wire 64 leads to the wire 61, to the bulb, 45 to ground, back to the battery.

Upon striking the segment "R" in any 50 of the four targets an "out to right field" is registered by a momentary flashing of the bulb D''. This is so because of the following connections, in addition to the wire 47 55 which leads from the battery 41 and has branches each of which goes to one of the contacts 31. From the collar 24 associated with the "R" segment of the target 18 a wire 65 having the bulb D'' interposed therein 60 leads to ground, back to the battery. From the collar 24 associated with the "R" segment of the target 19 a wire 66 leads to the wire 65, to the bulb, to ground, back to the battery. From the collar 24 associated with the "R" segment of the target 20 a wire 65

leads to the wire 65, to the bulb, to ground, back to the battery. And from the collar 24 associated with the "R" segment of target 21 a wire 68 leads to the wire 65, to the bulb, to ground, back to the battery. 70

In order that a normally open circuit may be manually closed to simultaneously energize all of the three magnets 19^C, 20^C and 21^C, so as to bring about a positive release of the latches 36 relative to such indicators 32 as 75 are in "safe" position, when desired, the following connections are provided: From battery 41 a wire 69 leads to a switch 70, and from the switch a wire 71 leads to the magnet 19^C, to ground, back to the battery. 80 From the wire 71 leads a wire 72 to the magnet 20^C, to ground, back to the battery. And from wire 72 leads a wire 73 to the magnet 21^C, to ground, back to the battery.

It will thus be seen that a rifleman may 85 play the game as follows: First he fires at the target 18, but none of the segments are free to close any of the circuits gaped at the collars 24 unless the ball 14 is actually passing over the plate 12 at the instant he 90 fires. If he hits the segment "H" of this target and causes it to vibrate, a run will be flashed at 18^P. If he hits one of the segments "L," "C" or "R" of this target, he 95 will fly out to left, center or right field. If he hits one of the segments "1," "2" or "3" of this target, he gets a safe indication at 19^P, 20^P or 21^P. If he makes a safe "advance" to either of these three base points, he commences firing at the target adjacent 100 that point. The segments of the targets at these three points are also prevented from vibrating unless the ball 14 is passing over the plate 12. When firing at either of the four targets 18, 19, 20 or 21, a striking of 105 any one of the segments "L," "C" or "R" will put him out at "left," "center" or "right" field. When firing at the target 19, he can advance to second base or to third base or else come home. When firing at the 110 target 20, he can advance to third base or come home. When firing at the target 21, he can come home. He can thus keep firing, making as many runs as he chooses, until he strikes one of the segments "L," "C" or "R" 115 and thereby registers an "out." One rifleman may play the game alone, or two or more can compete; for instance, two riflemen may commence the game together, one endeavoring to make as many runs as possible before the other succeeds in causing the registration of three outs.

I claim:

1. Apparatus of the kind described comprising a board having thereon the representation of a baseball field including base points, a target at one of said base points, a target at the next succeeding base point, a signal at said succeeding base point, and means operative upon the striking of the 125 130

first named target to cause an actuation of the signal at said succeeding target.

2. Apparatus of the kind described comprising a board having thereon the representation of a baseball field including base points, a two-part target at one base point, a signal adjacent the succeeding base point, means operative upon the striking of one of the two target parts at the first named base point for causing an actuation of the signal at the succeeding base point, a second signal, and means operative upon the striking of the other target-part at the first named base point to cause actuation of said second signal.

3. Apparatus of the kind described comprising a board having thereon the representation of a baseball field including base points, a target at one of said base points, a target at the next succeeding base point, a signal at said succeeding base point, means operative upon the striking of the first named target to cause an actuation of the signal at said succeeding target, and a moving member controlling said targets.

4. Apparatus of the kind described comprising a board having thereon the representation of a baseball field including base points, a two-part target at one base point, a signal adjacent the succeeding base point, means operative upon the striking of one of the two target-parts at the first named base point for causing an actuation of the signal at the succeeding base point, a second signal, means operative upon the striking of the other target-part at the first named base point to cause actuation of said second signal, and a moving member controlling said targets.

5. Apparatus of the kind described comprising a board having thereon the representation of a baseball field including base points, a target at one of said base points, a target at the next succeeding base point, a signal at said succeeding base point, and electro-magnetic means operative upon the striking of the first named target to cause an actuation of the signal at said succeeding target.

6. Apparatus of the kind described comprising a board having thereon the representation of a baseball field including base points, a two-part target at one base point, a signal adjacent the succeeding base point, electro-magnetic means operative upon the striking of one of the two target-parts at the first named base point for causing an actuation of the signal at the succeeding base point, a second signal, and electro-magnetic means operative upon the striking of the

other target part at the first named base to cause actuation of said second signal.

7. Apparatus of the kind described comprising a board having thereon the representation of a baseball field including base points, a target at one of said base points, a target at the next succeeding base point, a signal at said succeeding base point, electro-magnetic means operative upon the striking of the first named target to cause an actuation of the signal at said succeeding target, and a moving member controlling said targets.

8. Apparatus of the kind described comprising a board having thereon the representation of a baseball field including base points, a two-part target at one base point, a signal adjacent the succeeding base point, electro-magnetic means operative upon the striking of one of the two target-parts at the first named base point for causing an actuation of the signal at the succeeding base point, a second signal, electro-magnetic means operative upon the striking of the other target-part at the first named base to cause actuation of said second signal, and a moving member controlling said targets.

9. Apparatus of the kind described comprising a board having thereon the representation of a baseball field including base points, a multi-part target at each base point, and "safe" and "out" signals controlled by said targets.

10. Apparatus of the kind described comprising a board having thereon the representation of a baseball field including base points, a multi-part target at each base point, "safe" and "out" signals controlled by said targets, and a moving element supervising the control of said signals by said targets.

11. Apparatus of the kind described comprising a board having thereon the representation of a baseball field including base points, a multi-part target at each base point, "safe" and "out" signals controlled by said targets, and electro-mechanical means through which said control is effected.

12. Apparatus of the kind described comprising a board having thereon the representation of a baseball field including base points, a multi-part target at each base point, "safe" and "out" signals controlled by said targets, a moving element supervising the control of said signals by said targets, and electro-mechanical means whereby said control and said supervision are effected.

In testimony whereof I affix my signature.

AUGUSTUS M. HENRY.
